151,620

DESIGN FOR A MUSIC CABINET

Stanley F. Grabowski, San Mateo, and Joseph M. Sawaya, San Anselmo, Calif.

Application April 25, 1947, Serial No. 138,617

Term of patent 3½ years

(Cl. D56—4)

To all whom it may concern:

Be it known that we, Stanley F. Grabowski and Joseph M. Sawaya, citizens of the United States, residing at 410 E. Poplar, San Mateo, and 16 Bolinas Avenue, San Anselmo, respectively, in the counties of San Mateo and Marin, respectively, and State of California, have invented a new, original, and ornamental Design for a Music Cabinet, of which the following is a specification, reference being had to the accompanying drawing, forming part thereof.

Fig. 1 is a perspective view of a music cabinet showing my new design.

Fig. 2 is a side view of the cabinet shown in Fig. 1.

Fig. 3 is a top view of the cabinet shown in Fig. 1.

Fig. 4 is a horizontal cross-sectional view of the cabinet shown in Fig. 1 taken at a point midway between the top and bottom.

We claim:

The ornamental design for a music cabinet, as shown.

STANLEY F. GRABOWSKI.
JOSEPH M. SAWAYA.
